Primary Examiner — Sheryl Lane*Assistant Examiner* — Aula Soroush(74) *Attorney, Agent, or Firm* — Daniel J. Chalker; Edwin S. Flores; Chalker Flores, LLP(57) **CLAIM**

The ornamental design for pet toy, as shown and described.

DESCRIPTION

FIG. 1 is a front perspective view of a pet toy;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is an exploded perspective view of a pet toy thereof. The broken lines in the drawings illustrate portions of the pet toy and form no part of the claimed design.
